UNITED STATES PATENT OFFICE

JOHN K. LITSINGER, OF ALLIANCE, OHIO

SIGNALING RECEPTACLE

Application filed March 12, 1929. Serial No. 346,458.

My invention relates to signaling receptacles more particularly adapted for being placed on the outside of houses, for receiving milk bottles, mail, and the like.

Such receptacles, located on the outside of houses, are frequently subject to petty pilferers, and the objects of the present invention include the provision of a receptacle having simple mechanical means for emitting an audible signal when a milk bottle is inserted or removed from the milk compartment thereof, and when mail is inserted or removed from the mail compartment by lifting the lid to the mail compartment.

These and ancillary objects are attained in the present invention, as will hereinafter be set forth in detail, and claimed.

A preferred embodiment of the invention is illustrated in the accompanying drawing forming part hereof, in which

Figure 1 is a top plan view of the improved signaling receptacle with portions in section, and showing a hinged shelf, with which the receptacle is preferably provided, lowered 25 for supporting a plurality of extra bottles;

Fig. 2, a side elevation thereof as in the direction of the arrows 2-2, Fig. 1; and

Fig. 3, a sectional view thereof as on line 3-3, Fig. 1, the shelf being swung upwards 30 to its preferred position when not in use.

Similar numerals refer to similar parts throughout the several views.

The improved signaling receptacle indicated generally at 10 includes a case 11 having side walls 11^a and 11^b, end walls 11^c and 11^d, a partition wall 11^e between the end walls, and a bottom wall 11^f covering the opening at the lower end of the rear end wall 11^c, the partition wall 11^e, and the side walls 11^a and 11^b, thus forming an upwardly opening milk bottle compartment 12, and a mail compartment 13.

The mail compartment has an upper opening provided with a hinged upwardly swinging cover 14, which is preferably hinged at 15 on the upper end of the partition wall 11^e which separates the milk bottle compartment from the mail compartment.

The mail compartment is preferably provided with a laterally swinging bottom cover

16 which is pivotally connected as by a hinge 17 with the bottom wall 11^f of the receptacle.

Accordingly mail may be inserted in the mail receptacle 13 by lifting the cover 14, and may be removed therefrom by swinging the bottom cover 16 to one side.

A shelf 18 is preferably connected by hinges 19 to the bottom wall 11^f at the lower end of the side wall 11^b. A link 20 is pivotally connected as by a pivot screw 21 at the rear side of the shelf 18, and at the other end the link is provided with a slot and pin connection with the rear end wall 11^c of the receptacle, as by means of a screw 22 extending through a suitable slot 23 in the link.

Accordingly the shelf 18 may be lowered to the position illustrated in Fig. 1 for supporting a plurality of extra bottles or may be raised to the position illustrated in Fig. 3, when not required for such use.

The receptacle is preferably secured to the side wall 24 of a house, spacers 25 being provided between the rear end wall 11^c and the house side wall 24 for permitting operation of the link 20.

Preferably on the outside of the side wall 11^a, a spring motor powered bell 26 is mounted. The bell is of a well known design, and is adapted to be rung by movement of a plunger 27 outwardly from the side wall 11^a so towards the bell.

The plunger 27 extends through a suitable aperture 28 in the side wall, and is normally spring pressed toward the milk bottle compartment by the bell mechanism.

The inner end of the plunger 26 may be provided with a head 29 against which the lower end of an actuating lever 30 slidably rests.

The upper end of the actuating lever 30 is provided with pivot means 31 supporting the lever upon the inside of the side wall 11^a, and the relative locations of the pivot means 31 and the head 29 are such that the actuating lever 30 slopes downwardly towards the center of the milk bottle compartment 12.

The outer surface of the lower end of the actuating lever 30 is spaced at 32 a distance from the inside of the opposite side wall 11^b, less than the diameter D of the lower large

end of a standard milk bottle 33, and the distance from the inside of the rear end wall 11^a to the opposite face of the partition wall 11^b is just sufficiently greater than the diameter of the standard milk bottle to permit 5 vertical removal or insertion of the same from the upwardly opening milk bottle compartment 12.

Accordingly when such a bottle 33 is either 10 inserted in or removed from the milk bottle compartment 12, the lower end of the bottle will slide against the outer surface of the lower end of the actuating lever 30, thereby pushing the plunger 27 outwardly and ringing 15 the bell 26 for signaling the occupants of the house that the bottle has either been placed in the compartment or has been removed therefrom.

A similar bell 26' is mounted on the out- 20 side of the side wall 11^a adjacent the bell 26, and a cover 34 may be supported by spring clips 35 secured upon the side wall 11^a for protecting both bells from the elements.

The bell 26' includes an upwardly extending 25 plunger 27', normally spring pressed upwardly by the bell mechanism, and the plunger 27' extends through an aperture 37 in the bell cover 34, and is pivotally connected at its upper end with the outer end 30 of an actuating arm 36 extending rearwardly from the mail compartment cover 14; whereby when the mail compartment cover 14 is raised, the bell 26' will be rung, thereby signaling the event to the occupants of the house.

35 Accordingly, by the foregoing construction and arrangement, a simple and effective mechanical signaling receptacle is provided which permits the occupants of the house to be informed when a milk bottle is inserted 40 in or removed from the milk bottle receptacle or when the cover of a mail compartment is raised.

The mechanical signaling receptacle of the 45 present invention is superior to a signaling receptacle including electrically operated mechanisms, because such electrically operated mechanisms require batteries or other sources of electric power, and frequently necessitate the drilling of holes through the 50 side wall of the house.

I claim:

A signaling receptacle including box walls forming a closed receiving compartment, the 55 compartment having an opening permitting the insertion or removal of an article into or from the compartment, mechanically actuated signaling means, and a plunger for actuating the signaling means extending into the compartment and located in the path of an 60 article inserted or removed through the opening for operating the signaling means whenever an article is inserted or removed.

In testimony that I claim the above, I have hereunto subscribed my name.

65 JOHN K. LITSINGER.
